GARMENT

Morris A. Einbinder, Denver, Colo.

Application June 27, 1942, Serial No. 448,724

2 Claims. (Cl. 2—247)

This invention relates to improvements in garments and has reference more particularly to a method of constructing garments in such a way that they will have the appearance of being formed with patch pockets, belts and cuffs, without the additional expenditure of cloth that is necessary with the ordinary constructions.

It is the principal object of this invention to provide a method by means of which large quantities of woollen cloth can be saved without sacrificing appearance or style.

Another object is to produce a garment, a coat for example, that will have the appearance of having patch pockets but which can, in a few minutes and with the expenditure of a very small amount of labor be changed so as to eliminate the patch pocket effect.

A further object is to produce a pair of pants or the sleeves of a coat of such construction that they will have the appearance of having cuffs and which can readily be changed so as to eliminate this effect. At present there is great need of conserving woollen goods and the Government has issued regulations which inter alia prohibit the manufacture of men's garments with "patch pockets" and of trousers with cuffs.

The patch of an ordinary "patch pocket" of a man's coat and of the type shown in Figures 1 and 2 have a width of six (6) inches, and a depth of six inches and is provided with a central vertical pleat that requires an additional three (3) inches of cloth; this requires a patch 6 x 6 inches which has an area of fifty-four square inches. If the coat has two pockets one hundred eight square inches of cloth are required and if it has four pockets two hundred sixteen square inches are required for the patches. With my invention the same effect can be produced without the expenditure of any additional cloth. By my invention the effects of belts and cuffs can likewise be obtained without the use of additional cloth.

The above objects are attained by means of a method of construction that will now be described in detail and reference for this purpose will be had to the accompanying drawing where the invention has been illustrated, and in which:

Figure 1 is a view showing the appearance of a pocket made in accordance with my invention;

Figure 2 is a section taken on line 2—2, Figure 1 to approximately twice the scale;

Figure 3 is a section taken on line 3—3, Fig. 1, to approximately twice the scale; and

Figure 4 shows a pocket of a different style. In the drawing numeral 10 indicates a garment which, in this instance, is a man's coat; the

woollen cloth has been designated by numeral 11; the lining has not been shown. In order to form the pocket shown in Figure 1, the cloth is cut horizontally at 12. Beginning at the ends of cut 12 the cloth is folded along vertical lines 13 and 14 in the manner shown in Figure 2 and the material forming the fold or pleat is secured by stitching 15. A fold 16, parallel with cut 12, outlines the bottom which is joined to the vertical sides 13 and 14 by rounded corners 17. A tape 18 is usually interposed between the intermediate and the outer layer of the fold as shown in Figure 2.

Where a central pleat effect is desired two spaced vertical folds 19 and 20 are provided and secured by stitching 15. An outside flap 21 may be provided as shown in Figure 1 or omitted as in Figure 4.

Referring now to Figure 3 it will be seen that the upper end of the cloth 11 that forms the "patch" portion of the pocket is folded inwardly as indicated by numeral 22. A flap 23 is folded along line 24 and the downwardly extending portion 25 is folded inwardly and upwardly and connected to the fold 22 by stitching 26. Seams or stitching 27 and 28 secure the folded fabric in position. The material 29 that forms the pocket proper has one edge secured to flap 23 by stitches 30.

The upper end of flap 21 extends through the cut 12 and is secured between the lower folded end of the cloth 11 and the flap 31 by stitches 32. The inner side of pocket 29 is attached to flap 31 by stitches 33.

It will be seen from Figure 3 that the construction of the pocket is substantially the same as of any ordinary pocket, the difference being that the cloth 11 on the outside of the pocket 21 is folded along 13, 14, 16 and 17 to form an outline which has the appearance of a patch. If a vertical pleat effect is desired the goods is folded along vertical lines 19 and 20. The finished pocket has the appearance of a "patch pocket" but it requires no more cloth than an ordinary pocket. The material forming the folds is secured by the stretch of the cloth and there is no wrinkling of the cloth at the bottom as might be expected.

The pocket illustrated in Figure 4 is substantially the same as that shown in Figure 1 but instead of having a flap 21 it has a band 34.

50 If, for any reason, the owner or prospective purchaser of a garment having a "patch pocket" constructed as above described, should prefer an ordinary style of pocket, the seams 15 can be ripped and the goods pressed whereupon the "patch pocket" effect is eliminated. Such a

change can be made by a merchant in a few minutes and at practically no expense.

From the above description it will be seen that the appearance of "patch pockets" can be attained without the use of additional cloth. Where 5 large numbers of garments are manufactured, as for example Army and Navy uniforms, the saving in material becomes very substantial.

The fact that a garment can be made so as to have the appearance of having patch pockets and that it can be readily altered so as to remove this effect is of great importance to the garment trade as a retailer can then furnish the garment in either style without having to carry an additional stock. 10

Having described the invention what is claimed as new is:

1. A garment having an elongated opening forming the entrance to a pocket, in which the material on one side of the opening is formed into 20 a Z-shaped fold extending between the ends of

the opening, the area enclosed between the fold and the opening being of the size and shape of an ordinary patch pocket patch, the three layers of the fold being connected by stitches the outer surface of the material enclosed between the opening and the fold being displaced outwardly by the fold at least twice its thickness whereby the appearance of a "patch pocket" is obtained without the use of any additional material.

2. An imitation patch pocket for garments comprising a substantially U-shaped seam formed by folding portions of the material outwardly upon itself to represent the sides and bottom of a pocket, the area of the material defined by the 15 seam being offset from the surface of the remainder of the material outwardly with respect thereto, said seam including triple layers of material and comprising an inner layer, an intermediate layer and an outer layer, and stitching securing together at least two of said layers.
